UNITED STATES PATENT OFFICE.

JOSEPH A. POIRIER, OF WOONSOCKET, RHODE ISLAND.

BINDING-PAPER-FEED MECHANISM.

1,007,236.

Specification of Letters Patent. Patented Oct. 31, 1911.

Application filed May 8, 1911. Serial No. 625,706.

To all whom it may concern:

Be it known that I, JOSEPH A. POIRIER, a subject of the King of Great Britain, residing at Woonsocket, in the county of Providence and State of Rhode Island, have invented new and useful Improvements in Binding-Paper-Feed Mechanism, of which the following is a specification.

My present invention relates to binding-paper feed mechanism for use on box staying machines; and it has for its object to provide improved mechanism for said purpose, calculated to take secure hold of and feed binding-paper forward, and this without liability of causing retrograde movement of the binding-paper, which at the time of said feeding is moist and gummed at its underside, and the consequent interference with the operation of the machine as well as loss of binding-paper.

With the foregoing in mind, the invention will be fully understood from the following description and claims when the same are read in connection with the drawings, accompanying and forming part of this specification, in which:

Figure 1 is a side elevation of my novel mechanism, with the side guide wires partly broken away. Fig. 2 is a horizontal section taken in the plane indicated by the line 2—2 of Fig. 1, and also showing parts of the side guide wires broken away. Fig. 3 is a transverse section taken in the plane indicated by the line 3—3 of Fig. 2, looking toward the right.

Similar letters designate corresponding parts, in all of the views of the drawings, referring to which:

A is a base plate, designed to be fixed in a suitable manner with respect to the frame of a box staying machine (not shown).

B is an upright, longitudinally slotted guide plate fixed with respect to said base plate.

C are the side guide wires for the binding-paper.

D is the longitudinal-central wire that operates with the side wire in the guidance of the binding-paper.

E is a rectilinearly-movable carriage, disposed at one side of the plate B and having a portion *a* disposed in the slot *b* thereof, and also having studs *c* disposed laterally at the rear side of the plate B. F is a wear plate loosely mounted on said studs and arranged against the rear side of the plate B.

G is a bowed spring secured on the studs *c* and serving to yieldingly hold plate F against the plate B with a view to preventing lateral play of the carriage E.

H is an angle plate fixed with respect to the frame formed by the plates A and B.

I is a vertically swinging rock arm, fulcrumed at *d* on the carriage E and carrying a jaw J designed to grip the upper side of a binding-paper, and K is a bar designed to be actuated from any suitable working part (not shown) of the box staying machine. These parts, with the exception hereinafter noted, may be and preferably are of the ordinary construction well known in the art. I would have it understood, however, that the said parts may be of any other construction consonant with the purpose of my invention without involving departure from the scope of the same as defined in the claims appended.

In furtherance of my invention I provide the rock-arm I with a cam or tappet M, and I also provide a vertically-swinging plate N, pivoted at *e* to the opposite side of the carriage E, with reference to the guide plate B, and having a recess *f* in which the said cam or tappet M of the rock-arm I is disposed, and a jaw P carried by and disposed laterally to the plate N, and designed to grip the underside of the binding paper.

In practice as the carriage E is, through the bar K, moved toward the left, Fig. 1, the jaw J is moved down against the binding paper, and at the same time the cam or tappet M moves the plate N and the jaw P upward, with the result that the binding paper is securely gripped between the jaws and the paper is positively moved or fed in said direction. On the back movement of the carriage E—*i. e.*, from left to right, the bar K swings the arm I and raises the jaw J, while the cam or tappet M depresses the plate N and thereby moves the jaw P downward.

In other words, both jaws are positively moved out of engagement with the binding paper, and hence there is no liability of the binding paper, which as before stated is then in a moist state and gummed at its underside, being carried backward by the lower jaw P. This will be appreciated as an important advantage when it is borne in mind that where the lower jaw of binding-paper feed mechanism is fixed against vertical movement, the tendency of said lower jaw to carry the binding papers back

with it on the back or idle stroke of the carriage E not only interferes with the operation of the staying machine, but results in the waste of considerable binding paper.

5 While it is preferable to have the upper jaw J of the mechanism move down and up incidental to the reciprocation of the carriage E to assist in threading the binding paper or tape through machine it is not essential that jaw J be so movable or that it move at all with respect to the carriage, this because there is no paste at the upper side of the tape to adhere to the upper jaw. I therefore do not desire to be understood as 10 confining myself to an upper jaw or abutment movable on the carriage.

Having described my invention, what I claim and desire to secure by Letters-Patent, is:

20 1. In binding-paper feed mechanism, the combination of a rectilinearly-movable carriage, means for guiding the same, a rock-arm fulcrumed on the carriage and carrying a jaw and a cam, a bar connected to said arm and through which the arm is rocked and the carriage moved, and a swinging plate carried by the carriage in position to be moved by said cam of the rock-arm and having a jaw opposed to the one on the 25 rock-arm.

30 2. In binding-paper feed mechanism, the combination of a rectilinearly-movable car-

riage, means for guiding the same, a vertically-swinging rock-arm fulcrumed on the carriage and having a forwardly extending 35 and vertically-movable portion on which is a jaw and also having a rearwardly-extending cam, a bar connected to said rock-arm and through which the arm is rocked and the carriage moved, and a vertically-swinging plate carried by the carriage and having a recess in which said cam is disposed and also having a vertically movable jaw opposed to the one on the rock-arm.

3. In binding-paper feed mechanism, the 40 combination of a rectilinearly-movable carriage, means for guiding the same, a vertically swinging rock arm fulcrumed on the carriage and having a cam, a bar connected to said rock arm and through which the arm is rocked and the carriage moved, a vertically swinging plate carried by the carriage and having a recess in which said cam is disposed and also having a vertically movable 45 jaw, and an upper jaw carried by the carriage and opposed to said vertically movable 50 jaw.

55 In testimony whereof I have hereunto set my hand in presence of two subscribing witnesses.

JOSEPH A. POIRIER.
